O. J. Henkel,
ATTORNEY

UNITED STATES PATENT OFFICE.

FRANK P. GILL, JR., OF EAST CLEVELAND, OHIO, ASSIGNOR TO THE FERRO MACHINE AND FOUNDRY CO., OF CLEVELAND, OHIO, A CORPORATION OF OHIO.

PISTON.

Application filed February 18, 1924. Serial No. 693,438.

My invention relates to piston structures such as are used in cylinders of engines, pumps, etc., particularly in internal combustion engines.

5 The main object of my invention is a piston which is light in weight, sufficiently strong for the purpose intended, easily cast in the rough, easily machined, and more economical than present pistons. Other objects 10 will appear during the description of the piston shown in the accompanying drawing.

It is well known in engine structures, particularly in internal combustion engines, that the weight of the piston has considerable 15 bearing on the efficiency of the engine. Light weight material has been tried for piston purposes but such material is more expensive, wears faster, and a piston made of such material does not last long, thereby 20 losing more in repairs and displacements than has been saved in efficiency even if the cost of the heavy and the light pistons were the same; usually however pistons made of 25 light weight material cost more than pistons made of heavy weight material.

In order to retain the advantages found in pistons made of heavy weight material and attain the additional efficiency due to a light weight piston, or to further reduce the 30 weight of the present heavy weight pistons and thereby gain further in efficiency, I have invented certain piston structures and show one application of my invention in the accompanying drawing wherein I attain my 35 objects and in which

Fig. 1 is a perspective view of a piston for an internal combustion engine embodying the features of my invention; Fig. 2 is a section, taken on a vertical plane indicated 40 by the line 2—2 in Fig. 1, showing the longitudinal relation of the piston-pin bosses and the ribs and the other portions of the piston; Fig. 3 is a section, taken on a vertical plane indicated by the line 3—3 in Fig. 1, 45 showing the longitudinal relation of the upper and the lower and the intermediate cylinder bearing portions and the piston-pin bosses and the ribs; Fig. 4 is a section, taken on a horizontal plane indicated by the line 4—4 in Fig. 2, showing the transverse relation 50 of the upper rib structure to the piston-pin bosses and the other piston portions; and Fig. 5 is a section, taken on a horizontal plane indicated by the line 5—5 in Fig. 55 2, showing the transverse relation of the

bosses and the lower rib structure to the other portions of the piston.

Similar reference characters refer to similar parts throughout the views.

The general features of the present invention are to cut away or eliminate material where it can be dispensed with or where it serves no useful purpose and to adequately strengthen and stiffen the material which is needed in the structure for useful purposes. 60 In pistons for internal combustion engines for instance, it has formerly been the practice to make the outer circumferential wall solid all around but it has been found necessary to relieve portions of the outer surface 70 of this wall, around the piston-pin, to get better action out of the piston. This necessity of so relieving these portions requires a certain amount of time and labor and these relieved portions of the piston really 75 serve no useful purpose but add to the weight of the piston.

The present invention eliminates these relieved portions entirely and strengthens the remaining and useful portions thereby saving 80 time and labor in machining the piston, saving material in the original casting for the piston, providing a light weight piston of sufficient strength, and increasing the efficiency of the engine in which the piston is 85 used.

Referring now particularly to the drawing.

The piston shown in the drawing consists, principally, of the upper cylinder bearing 90 portion A, the lower cylinder bearing portion B, the intermediate cylinder bearing portion C, and the piston-pin supports D.

The portion A has the outer circumferential wall 10 fitting to the wall of a cylinder 95 and is provided with the ring grooves 11, and has the top wall 12 to close the top of the portion A. The rib 13 is disposed on the under side of the wall 12 and extends across this wall at right angles to the axis of the 100 piston-pin openings 14.

The portion B has the outer circumferential wall 15 fitting to the wall of the engine cylinder and is provided with the inwardly 105 extending circular ribs 16 and 17.

The portions C extend longitudinally between and connect the portions A and B, are disposed diametrically opposite each other and substantially at right angles to the axis 110 of the piston-pin openings 14, and are com-

paratively narrow; thereby providing the openings E on each side thereof.

Each of the portions C has the outer circumferential wall 18 fitting to the wall of 5 the engine cylinder and is provided with the inwardly extending longitudinal rib 19 extending from the circular rib 17 to the portion A. For the purpose of strength of the 10 piston, and for convenience in casting the piston, and for preventing checks or cracks in the piston while it is being cast, it is preferred to introduce the fillets 20 and 21 where the portion C connect with the portions A and B respectively.

15 The supports D extend longitudinally between and connect the portions A and B, are disposed in the openings E, diametrically opposite each other and intermediate the portions C, preferably substantially at right 20 angles to the portions C.

Each of the supports D has the piston-pin boss 22 provided with the opening 14 to accommodate a piston-pin or a bushing therefor. It is observed that the outside face 24 25 of each of the bosses 22 is inside of the outer circumferential surface of the portions A, B, and C, so that the bosses 22 do not touch the wall of the engine cylinder, therefore, only the portions A, B, and C contact this 30 wall and these portions only need to be finished or machined.

Each of the bosses 22 is connected to the portion A by the circumferential rib 25 which extends from substantially midway of 35 the top of the boss up to the portion A; the upper portion 26 of the rib 25 being inclined as shown in Fig. 2 to provide additional strength in the piston. The ribs 25 are, preferably, provided with the fillets 27 for purposes similar to the fillets 20 and 21 previously described.

The transverse ribs 28 are disposed on the outside of the ribs 25, extend from the top of the bosses 22 up to the portions 26, and 45 the outer ends thereof are flush with the respective bosses.

The transverse ribs 29 are disposed on the inside of the ribs 25 and on the inside of the portion A and extend from the top of 50 the bosses 22 up to the inside of the wall 10 where they are, preferably, provided with the fillets 30 for purposes similar to the fillets previously described.

Each of the bosses 22 is connected to the portion B by the circumferential rib 31 which extends from the outer end of the bottom of the boss down to the portion B. The ribs 31 are, preferably, provided with the fillets 32 for purposes similar to the fillets 60 previously described.

The transverse ribs 33 are disposed on the inside of the ribs 31 and extend from the bottom of the bosses 22 down to the portion B.

65 It is observed that the piston structure

shown and described embodies rigidity and minimum weight and minimum machine work and minimum material in the original casting or in the original blank when made of pressed or otherwise formed material. 70

I am aware that pistons have been made with portions of the outer circumferential surface thereof, around the piston-pin, have been relieved; therefore, I do not claim such feature broadly; I am also aware that modifications may be made from the structure shown and described, within the scope of the appended claims; therefore, without limiting myself to the precise structure shown and described, I claim: 80

1. A piston including, an upper cylinder bearing portion provided with a top wall, a lower cylinder bearing portion provided with an inwardly extending flange, two intermediate cylinder bearing portions opposite each other and extending longitudinally of the piston and connecting said upper and said lower bearing portions, two piston-pin bosses opposite each other and intermediate said intermediate bearing portions and extending longitudinally of the piston and connecting said upper and said lower bearing portions, ribs connecting said bosses with said upper and said lower bearing portions and with said wall; and the outer surface of 85 said bosses and of said ribs below the outer circumferential surface of said cylinder bearing portions. 90

2. A piston including, an upper cylinder bearing portion provided with a top wall, a lower cylinder bearing portion, two intermediate cylinder bearing portions opposite each other and extending longitudinally of the piston and connecting said upper and said lower bearing portions, two piston-pin 100 bosses opposite each other and intermediate said intermediate bearing portions and extending longitudinally of the piston and connecting said upper and said lower bearing portions, 105 circumferential ribs extending from substantially midway of the top of said bosses to said upper bearing portion, transverse ribs extending from the top of 110 said bosses to said upper bearing portion on the outside of said circumferential ribs, 115 transverse ribs extending from the top of said bosses to said upper bearing portion and to said top wall on the inside of said circumferential ribs, and ribs connecting the bottom of said bosses to said lower bearing portion. 120

3. A piston including, an upper cylinder bearing portion provided with a top wall, a lower cylinder bearing portion provided with an inwardly extending flange, two intermediate cylinder bearing portions opposite each other and extending longitudinally of the piston and connecting said upper and said lower bearing portions, two piston-pin 125 bosses opposite each other and intermediate 130

said intermediate bearing portions and extending longitudinally of the piston and connecting said upper and said lower bearing portions, ribs connecting the top of 5 each of said bosses to said upper bearing portion and to said top wall, circumferential ribs extending from the bottom and the outside of said bosses to said lower bearing portion, and transverse ribs extending from 10 the bottom of said bosses to said lower bearing portion on the inside of said circumferential ribs.

4. A piston including, an upper cylinder bearing portion provided with a top wall, a 15 lower cylinder bearing portion provided with an inwardly extending flange, two intermediate cylinder bearing portions opposite each other and extending between and connecting said upper and said lower bearing 20 portions, a longitudinal rib on the inside of each of said intermediate bearing portions, two piston-pin bosses opposite each other and intermediate said intermediate bearing portions and intermediate said upper 25 and said lower bearing portions, circumferential ribs extending from substantially midway of the top of said bosses to said upper bearing portion, transverse ribs extending from the top of said bosses to said 30 upper bearing portion on the outside of said circumferential ribs, transverse ribs extending from the top of said bosses to said upper bearing portion and to said top wall on the inside of said circumferential ribs, 35 circumferential ribs extending from the bot-

tom and the outside of said bosses to said lower bearing portion, and transverse ribs extending from the bottom of said bosses to said lower bearing portion on the inside of said second circumferential ribs. 40

5. A piston comprising a head having an adjacent ringed portion, wrist pin bearings, a skirt forming an extension of said ringed portion cut away with the exception of narrow segments symmetrical with a plane perpendicular to the axis of said wrist pin bearings and an annular portion at the lower end of said segments, and reinforcing webs connecting said bearings with said annulus, ringed portion and head. 50

6. A piston comprising a head, a ringed portion adjacent thereto, a skirt forming an extension of said ringed portion cut away with the exception of narrow segments symmetrical with an axial plane and an annular portion at the lower end of said segments, 55 wrist pin bearings located in the cut-away portion of said skirt, and webs connecting said wrist pin bearings with said annulus, head and skirt. 60

7. A piston comprising a head, an adjacent ringed portion, wrist pin bearings, angled webs which merge in conical shapes connecting said ringed portion and said bearings, and a skirt cut away opposite said bearings and providing narrow segments symmetrical to a plane transverse to the axis of said bearings connected by an annular portion at their lower ends. 65
